UNITED STATES PATENT OFFICE

MAX PAUL ERNST HOHN, OF DRESDEN, GERMANY, ASSIGNOR TO THE FIRM "UNIVERSALLE" CIGARETTENMASCHINEN FABRIK J. C. MULLER & CO., OF DRESDEN, GERMANY

CIGARETTE ROD CUTTING DEVICE FOR CIGARETTE MACHINES

Application filed June 20, 1929, Serial No. 372,387, and in Germany February 20, 1929.

The present invention relates to a cigarette rod cutting device for use with cigarette rod machines in which there is used for severing the cigarette rod a rotary cutter the shaft of which is mounted on a support the axis of rotation of which is approximately parallel to the longitudinal direction of the cigarette rod. The cutter shaft is thus separately set in rotation by the rotation of the 10 preferably disc-shaped support.

The invention is characterized by the following arrangements:—

(a) The arrangement of the cutter shaft bearing on a disc or like support the plane 15 of which is at right angles to the longitudinal axis of the shaft carrying it, the cutter shaft being shiftable in relation to the disc and the supporting shaft being shiftable in relation to the rod.

(b) The arrangement that the supporting shaft is mounted in a hollow bearing head which is arranged in the form of a turntable on a bearing bracket in which is mounted the upright driving shaft for the 25 supporting shaft about the longitudinal axis of which the turntable movement takes place, the motion being transmitted between the two shafts by bevel gearing.

(c) The arrangement that the bearing 30 bracket is rendered movable and adjustable with the upright driving shaft and the bearing of the supporting shaft carried thereby about a horizontal axis on which shaft is arranged a worm wheel which meshes with a worm or the like on the upright shaft.

(d) The arrangement that the bearing bracket of the cutter shaft may turn on a support provided on the cutter shaft support in order to facilitate rotation of the 40 longitudinal axis of the cutter shaft in a plane transversely of the plane of the disc-shaped cutter support.

(e) The arrangement that the plate for the cutter shaft bearing is secured to a slide 45 movable and adjustable radially with respect to the supporting shaft while a balancing counter-weight is movably and adjustably secured on a second diametrically disposed slide, an adjusting device being provided which on unscrewing the fastening screws

moves the two slides together in the direction to maintain the balance.

(f) The arrangement that the adjusting device consists of a screw-threaded spindle which engages a counter-weight guided parallel to the axis of the spindle, this spindle being hollow and provided with an internal screw thread of opposite hand in which engages a screw threaded bolt mounted on a strap which is connected with the slide on 55 which the plate of the cutter shaft support is mounted.

(g) The arrangement that a friction wheel is mounted on the cutter shaft which contacts with a conical friction disc disposed concentrically of the axis of the cutter shaft support, the conical friction disc being longitudinally movable on the spindle supporting it i. e. longitudinally movable with respect to the cutter shaft, and thus being capable of adjustment 60 as regards its distance from the disc like cutter shaft support.

(h) The arrangement that the conical friction disc is mounted directly on the spindle of the cutter shaft supporting disc spindle 75 while the hub of the supporting disc is mounted on a bush mounted on this spindle in ball bearings provided at both ends, the drive being transmitted from the upright shaft by facing bevel pinions one of which is secured 80 directly to the spindle of the supporting disc while the other is connected to the hub of the disc shaped support.

(i) The arrangement that the relative adjustment of the bearing members and the adjustment about the horizontal axis of the cutter shaft bearing is effected by studs secured to one part which extend through corresponding slots on the other part disposed concentrically of the axis of rotation, scales being provided which permit of exact adjustment. 85

(k) The arrangement that the holder for the cutting tubes is secured to a cross bar carried by two parallel horizontally adjustable rods which project from a closed casing in 90 which the gearing is mounted, the connecting rod of a crank and connecting rod gearing being connected to a second cross bar provided in the casing which connects the two associated rods. 100

(l) The arrangement that the chamber in which the gearing for the cutting tube holder is closed by a cover in such manner that on removal of the cover the crank and connecting rod gearing is exposed for the purpose of adjustment.

(m) The arrangement that the bearing housings are connected with one another and the lubricating oil is circulated by a gear pump within it, a ventilating branch being provided.

(n) The arrangement of a grinding disc in the path of the rotary cutter rotating about the supporting spindle the bearing member of which is adapted to turn on a plate in a plane transversely of the plane of the supporting disc and adapted to be adjusted and secured in adjusted position, the plate being adapted to be adjusted in the longitudinal direction of the supporting axis.

(o) The arrangement of a freely rotatable setting disc the spindle of which is mounted in a bearing which is movable in a bearing bracket in a radial direction in relation to the cutter shaft supporting disc which can turn and be secured in adjusted position on a plate which is disposed in a plane transversely of the cutter shaft supporting disc, the support of the plate being movable and adjustable in the longitudinal direction of the disc carrying shaft.

The invention includes not only the combination of the arrangements (a) to (o) but also each arrangement separately so far as it is new.

The invention is illustrated in the accompanying drawings in which Fig. 1 is a vertical longitudinal section. Fig. 1a is a partial sectional view of a detail. Fig. 2 is a front view looked at in the direction of the arrow in Fig. 1 the conical friction disc being omitted. Fig. 3 is a plan view.

Referring to the drawings, the cigarette rod-cutting device is driven by the driving shaft 1. On this shaft is mounted a pinion 2 which transmits motion through the medium of the pinion 3 on the spindle 4 to the horizontal shaft 5 through the pinion 6. This shaft extends through a housing 7 and is mounted at its ends in the base 8 of the rod cutting device. On the end of this shaft projecting beyond the base 8 is fitted a hand wheel 9 in order to permit adjustment also by hand in which case naturally the driving shaft 1 must be freed from the machine drive in known manner.

Within the casing 7 is mounted on the driven shaft 5 a worm wheel 10 which meshes with a worm 11 located at the lower end of an upright shaft 12 the spindle 13 of which is secured at 14 to the bottom of the housing 7. The shaft 12 thus rotates about the spindle 13 and rests on a collar 15 on the spindle which serves as a foot step bearing. The housing 7 can be turned about the shaft 5,

the parts where the shaft extends through the wall of the casing being formed with suitable openings for the purpose. In this turning movement the worm naturally remains in mesh with the worm wheel 10. In order to secure the housing 7 in the position into which it has been moved three set screws 16, 17, 18 are secured to the base 8 and extend through slots 19, 20, 21 which extend parallel to the longitudinal axis of the shaft 5. The housing can be locked in any position by means of nuts on set screws. On the base 8 is provided a fixed scale 22 which is used in conjunction with a scale 24 provided on the bracket 23 on the housing 7. The desired adjustment can be therefore always obtained.

The upright shaft 12 extends through an upper opening 25 in the housing 7 and terminates in a bevel pinion 26. This bevel pinion meshes with two facing bevel pinions 27, 28 the bevel pinion 27 being mounted direct on the spindle 29 which is mounted in a housing 30 in ball bearings at 31, 32, 33. This spindle projects beyond the housing at the right hand side of Fig. 1 and is fitted with a conical friction disc 34 which is mounted on a bush 35 provided at one end with a number of longitudinal slits 36. The one end of this sleeve is formed as a cone 37 while the other end is provided with an external screw thread on which is screwed a nut 38. By unscrewing the nut 38 the conical friction disc 34 can be moved slightly to the right of Fig. 1 when the slits in the bush 35 expand permitting the bush to be pushed along the spindle 29. The bush can be locked in its new position by again tightening the nut 38 when the friction disc 34 is pressed against the cone 37 and the slit part of the bush compressed.

The bevel pinion 28 is freely rotatable on the spindle 29 and is secured by screws 39 to the hub 40 of a disc 41. This hub is freely rotatable in the hollow housing 30 in ball bearings 42, 43 located at each end while the ball bearings 32, 33 allow rotation of the spindle 29 with respect to the hub 40.

As the bevel pinions, 27, 28 face one another and are driven by the same bevel pinion 26 the spindle 29 is driven in one direction of rotation while the conical friction disc 34 is rotated in the opposite direction. In other words the disc 41 rotates in the direction of the arrow indicated in Fig. 2 while the conical friction disc 34 rotates in the opposite direction.

The axis of the spindle 29 is substantially parallel to the longitudinal direction of the cigarette rod but can be so adjusted that it intersects the longitudinal direction of the cigarette rod in a vertical or a horizontal plane. The inclined position of the spindle 29 in a vertical plane is obtained by turning the housing 7 while adjustment in the

horizontal plane is effected by turning the housing 30. For this purpose the upper part of the housing 7 in which the housing 30 is mounted is formed after the manner of a turntable. The housing 30 rests with its circular collar at 44 in a corresponding circular opening in the housing 7 in such manner that it may be rotated about the longitudinal axis of the upright shaft or about the spindle 13 which is effected so that nothing is disturbed by rotation of the bevel gearing. In order to secure the housing 30 in the desired position lugs 45, 46, 47 (see Fig. 3) are provided on the housing 7 in which fit studs 48, 49, 50 which extend through slots 51, 52, 53, in the corresponding lugs disposed on the rotatable housing 30.

Locking can be effected by nuts screwed on the studs rotation being permissible within the limits of the slots which are disposed concentrically of the spindle 13. A stationary scale 54 being provided on the housing 7 and a scale 55 provided on the housing 30 any desired adjustment can be obtained at any time by these two scales.

On the disc 41 driven by the upright shaft 12 through the bevel gearing, spindle 29 is radially movable a slide 56 which can be secured in any desired position on the disc 41 by means of bolts 57 and 58 which extend through slots 59 and 60 on the disc 41 disposed parallel to the direction of displacement. The slide carries a plate 62 which carries the plate 63 which forms the foot of a bearing 64 in which the cutter shaft 65 is rotatable. The plate 63 can be turned about the plate 62 and secured by the nuts 66 and 67 on studs secured to the plate 62 and extending through concentric slots in the plate 63. The cutter shaft carries the rotary cutter 70 held in known manner between clamping jaws 68 and 69. On the other end of the cutter shaft is mounted a friction roller 71 which contacts with the conical friction disc 34.

On radial displacement of the slide 56 and thus on bringing the cutter shaft nearer to or moving it further from the spindle 29, the conical friction disc 34 is correspondingly displaced longitudinally on the spindle 29 so as to ensure contact between the friction roller 71 and the conical friction disc.

As the conical friction disc 34 rotates in the opposite direction to the disc 41 additional rotation is imparted to the cutter shaft i. e. there is obtained a greater number of revolutions than would be obtained if the friction roller 71 merely rolled around a stationary conical friction disc 34.

The adjustment of the cutter shaft bearing on the plate 62 and the adjustment of the housing 30 and the adjustment of the housing 7 are so effected that the cutting edge of the rotary cutter 70 has a tumbling movement in which the cutter edge penetrating the cigarette rod moves with reference to the suc-

ceeding points with the speed of the rod in the direction of feed and the adjustment is such that the plane of the cutter at the moment that the cutting operation takes place is exactly at right angles to the longitudinal direction of the cigarette rod.

The radial displacement of the cutter shaft bearing is necessary on account of unavoidable wear of the rotary cutter in consequence of which the diameter of the rotary cutter alters. The rotary cutter becomes smaller in diameter in the course of use and a gradual displacement of the cutter shaft bearing radially outwards is necessary.

It is now essential that at the extraordinary high speeds of rotation absolute dynamic balance of the masses is produced. This balance is obtained by the counter-weight 72 which is radially displaceable on the disc 41, studs 73 and 74 secured to this disc extending through slots 75, 76 disposed parallel to the direction of displacement of the weight 72, the weight being locked in position by means of nuts on the studs. The counter-weight 72 engages by means of a bracket 77 in a radial slot 78 in the disc 41. This bracket is provided with a screw threaded opening through which extends a screw threaded spindle 79. This spindle is held by a collar 80 in the disc 41, or in a part 81 structually separate therefrom but connected therewith. After unscrewing the studs 73, 74 the weight 72 can be moved radially by rotation of the screw threaded spindle 79.

The spindle is hollow and is open at the lower end and provided with an internal screw thread of the opposite hand to the external screw thread of the spindle. Into the screw thread in the spindle extends a bolt 82 which is secured to a strap 83. The ends of this strap are secured to the slide 56 at 84 and 85. The strap embraces the spindle 29 or a lock nut 86 arranged thereon, the slide 56 on its end adjacent the spindle 29 having a corresponding recess 87. As the result of this arrangement, on rotation of the screw threaded spindle 79 movement the slide 56 and the counter weight are moved radially, dynamic balancing of the masses being thereby automatically effected.

The cigarette rod is supported as usual at the part where it is to be cut by the tubes 88 and 89 which are mounted in the bracket 90. This bracket is secured by means of set screw 91 to a cross bar 92 which is carried by the ends of two horizontal rods 93 and 94. The cross bar is movable on the ends of the rods. It has split jaws embracing the rods which jaws can be drawn together by screws 97 and 98. The rods 93 and 94 project from the housing 8 which forms at its lower side a chamber 99 into which the main shaft 1 extends. On the shaft is mounted a crank disc 100 on the adjustable crank pin 101 of which is pivoted a connecting rod 102. This con-

necting rod is pivoted at 103 to a bracket 104 to a second cross bar 105 which like the cross bar 102, is secured to the rods 93 and 94. Accordingly the rods are moved by the cross bar 105 in their bearings 106 and 107. The movement is such that the cutting tubes during the cutting operation when the rotary cutter 70 penetrates the rods are moved in the direction of feed of the rod with the speed of the rod.

In the housing 8 is mounted a gear pump the pinions 108 and 109 of which are driven by the main shaft 1 through the pinion 110. The chamber 99 is closed by a cover 99' (see Fig. 2) after removal of which (see Fig. 1) the crank and connecting rod gearing for the rods 93 and 94 is exposed so that any necessary adjustment can easily be effected.

On each rotation of the spindle 29 or of the cutter shaft supporting disc 41 the cutter comes into engagement with the grinding disc 111. (This grinding disc is omitted from Fig. 1 in order not to confuse the illustration but is indicated in Figs. 2 and 3). The grinding disc is mounted on a spindle 112 which is freely rotatable in the bearing 113. The bearing is carried by a bearing bracket 114 which terminates in foot plate 115 which is mounted on a base plate 116. With the base plate 116 is connected a stud 117, which passes through a slot 118 and a foot 115 of the bracket 114. After unscrewing the stud the foot 115 can be adjusted on the base plate 116, within the limits of the slot 118. The base plate 116 is formed as a slide and is movable on the guide 119 in the direction of the cigarette rod i. e. towards the disc 41. This movement is effected by means of a hand wheel 120, a spindle 121 connected with the hand wheel passing through the screw threaded lug 122 on the lower side of the slide 116. By the arrangement described the grinding disc 111 as regards its inclination and position can be brought into the path of the rotary cutter 70 so that the cutting edge of the cutter or its facet is sharpened on the grinding disc.

In order to remove the burr formed on the opposite side of the rotary cutter disc the setting disc 123 is provided, the spindle 124 of this disc is freely rotatable in the bearing 135. The bearing itself is movable and adjustable about the horizontal spindle 126. This spindle is carried by a bearing bracket 127 the foot 128 of which is mounted on a base plate 129. A stud 130 passes through the opening in the foot 128. After unscrewing the stud the bearing member 127 can be turned about the stud in a horizontal plane. The base plate 129 is carried by bracket 131 projecting from a slide 132. This slide is movable in the guide 133 parallel to the direction of the cigarette rod i. e. transversely of the disc by means of a hand-wheel 134 the screw threaded spindle 135 of which passes through a screw threaded opening in the slide

132. The setting disc 123 can thus be exactly adjusted to the position of the cutter at any time.

It is necessary that the connected chambers 89, 7 and 30 can be ventilated. For this purpose a ventilating pipe 136 is provided (see Fig. 1).

I claim:

1. A cigarette rod cutting device for cigarette machines including a cutter shaft, a rotary cutter mounted on said shaft and planetary gearing for driving the cutter shaft, a spindle, a slide movable and adjustable with respect to said spindle, a plate for the cutter shaft secured to said slide, a second slide, a counter-weight movably and adjustably secured on said second slide and adjusting means for moving the two slides together.

2. A cigarette rod cutting device for cigarette machines including a cutter shaft, a rotary cutter mounted on said shaft and planetary gearing for driving the cutter shaft, a spindle, a slide movable and adjustable with respect to said spindle, a plate for the cutter shaft secured to said slide, a second slide, a counter-weight movably and adjustably secured on said second slide and adjusting means for moving the two slides together, said adjusting device comprising a screw-threaded spindle, said counter-weight being engaged thereby, said spindle being hollow and provided with an internal screw thread of opposite hand in which engages a screw threaded bolt mounted on a strap which is connected with the slide on which the plate of the cutter shaft support is mounted.

3. A cigarette rod cutting device for cigarette machines including a cutter shaft, a rotary cutter mounted on said shaft, planetary gearing for driving the cutter shaft and a support for the cutter shaft, said planetary gearing comprising a friction wheel mounted on the cutter shaft, a conical friction disc disposed coaxially of the cutter shaft support and contacted by said friction wheel, said conical friction disc being longitudinally movable and means for driving said friction disc.

4. A cigarette rod cutting device for cigarette machines including a cutter shaft, a rotary cutter mounted on said shaft, a rotary support for said cutter mounted on a bushing on a rotary spindle, a conical friction disc mounted directly on said spindle, said bushing being provided with ball bearing support on said spindle, and gearing means for rotating said spindle and bushing, said means including an upright shaft having a bevel pinion adapted to mesh with two facing bevel pinions one of which is secured directly to said spindle while the other is connected to said bushing.

5. A cigarette rod cutting device for cigarette machines comprising a rotatable sup-

port, means to drive said support, a rotatable cutter mounted on said support, means for adjusting the position of said cutter on said support, adjustable means for continuously driving said cutter while said first named means is actuated and means for driving said adjustable means.

6. A cigarette rod cutting device for cigarette machines comprising a rotatable vibrating support, means to drive said support, a rotatable cutter mounted on said support, means for adjusting the radial position of said cutter on said support, adjustable means for continuously driving said cutter while said first named means is actuated and means for driving said adjustable means.

7. A cigarette rod cutting machine as per claim 5, in which said adjustable means for continuously driving said cutter comprises a displaceably mounted friction disc mounted on a rotatable shaft and a cooperating friction wheel connected to said cutter.

8. A cigarette rod cutting device for cigarette machines including a cutter shaft, a rotary cutter mounted on said shaft, a supporting disc for said cutter shaft, a rotatable shaft to which said disc is mounted, a second rotatable shaft concentric with said first rotatable shaft and rotatable independently of the latter, a conical friction disc mounted directly on said second named rotatable shaft and adapted to be movable longitudinally thereof, means for setting said friction disc at different points along said second rotatable shaft, a friction wheel on said cutter shaft adapted to engage said friction disc and means for rotating said two rotatable shafts in opposite direction from a common source.

9. A cigarette rod cutting machine as per claim 4, in which said upright shaft is mounted in a housing said housing being rotatable, and in which said spindle and bushing are mounted in a bearing which latter is mounted in turntable fashion to said housing whereby said spindle and bushing are rotatable in a plane at right angles to said upright shaft and driving means for rotating said upright shaft irrespective of the positions of said housing and bearing.

10. In a cigarette rod cutting machine having a rotatable cutter mounted on a rotatable support and a rotatable driver for rotating said cutter, said driver being mounted on a spindle and said support being mounted on a bushing concentric with said spindle, a bearing for supporting said bushing and spindle, an upright shaft having a pinion adapted to drive said bushing and spindle by meshing with two facing bevel pinions mounted respectively to said spindle and bushing, a bearing for supporting said upright shaft, said first named bearing being rotatable relative to said second named bearing and said second named bearing being rotatable relative to its

support and means for rotating said cutter support and said driver irrespective of the position of said bearings.

In testimony whereof I affix my signature.
